Age:

UNITED STATES PATENT OFFICE.

JAMES P. WALL, OF PITTSBURGH, PENNSYLVANIA.

METHOD OF MAKING HAND-WHEELS FOR VALVES.

1,287,531.

Specification of Letters Patent. Patented Dec. 10, 1918.

Original application filed May 24, 1916, Serial No. 99,651. Divided and this application filed June 25, 1918. Serial No. 241,891.

To all whom it may concern:

Be it known that I, JAMES P. WALL, a citizen of the United States, residing at Pittsburgh, in the county of Allegheny and State of Pennsylvania, have invented a new and useful Improvement in Methods of Making Hand-Wheels for Valves, of which the following is a full, clear, and exact description, reference being had to the accompanying drawings, forming part of this specification, in which—

Figure 1 is a plan view, partly broken away, of a hand wheel made in accordance with my invention.

Fig. 2 is a section on the line II—II of Fig. 1.

Fig. 3 is a side view showing the grip member partially formed, and

Fig. 4 is a sectional view of the partially completed wheel.

My invention has relation to hand wheels or handles for valve stems and the like, and more particularly, to devices of this character in which the hand grip is formed by a helix of wire seated upon a central member or core.

The object of the present invention is to provide a novel method for assembling a wheel of this character and as a result of which a superior wheel is produced.

The present application is a division of my application Serial No. 99,651, filed May 24, 1916, now Patent No. 1,272,738, issued July 16, 1918.

In accordance with my invention, I provide a central member or core 2, consisting of a hub portion perforated at 3, to receive the valve stem or spindle, and a rim portion. The member 2 is formed of brass, copper or other malleable metal, which can be bent or flanged, and is initially provided with the outwardly bent flange 4 at one end, the other end being left substantially unflanged. 5 designates a coil or helix of wire, and 6 an annular attaching member or band.

In the manufacture of this hand grip, the coil or helix 5, which has been cut to the proper length, is threaded upon the annular band 6, in the manner indicated in

Fig. 3. After the helix has been threaded upon the band in this manner the band and helix are then slipped over the unflanged end of the member 2, which it preferably fits snugly, and this end portion 2 is then flanged outwardly, as indicated at 7 in Fig. 55

2. This flanging causes the hand grip to be securely pinched between the flanges 4 and 7 and to be frictionally held thereby in a manner to prevent its rotation upon the member 2.

The invention provides a simple, efficient and practical method of forming articles of the described character rapidly and cheaply, and of superior quality.

When properly made in accordance with the invention, the hand grip cannot slip upon the core and the various coils of the grip are each frictionally clamped against the rim portion of the core, giving a firm gripping action to the handle.

I claim:

1. The herein described method of making hand wheels, which consists in providing a central member or core of malleable material and having a rim portion, threading a coil or helix upon an annulus, then placing said annulus with the coil or helix thereon upon the central member or core, and bending or flanging said member or core to confine and frictionally secure the hand grip thereon; substantially as described.

2. The herein described method of forming hand wheels, which consists in providing a central member or core of malleable material having a rim portion flanged at one end and substantially unflanged at its opposite end, providing a hand grip consisting of a coil or helix having an annular band therein, slipping said grip containing the annulus over the unflanged end portion of the core, and then flanging said end portion to confine the grip and frictionally securing it between the two flanges of the core; substantially as described.

In testimony whereof I have hereunto set my hand.

JAMES P. WALL.
